UNITED STATES PATENT OFFICE.

LEONARD F. FULLER, OF SAN FRANCISCO, CALIFORNIA, ASSIGNEE TO FEDERAL TELEGRAPH COMPANY, OF SAN FRANCISCO, CALIFORNIA, A CORPORATION OF CALIFORNIA.

RADIOTELEGRAPHY.

1,352,886.

Specification of Letters Patent. Patented Sept. 14, 1920.

Application filed September 19, 1917. Serial No. 192,209.

To all whom it may concern:

Be it known that I, LEONARD F. FULLER, a citizen of the United States, and a resident of the city and county of San Francisco and State of California, have invented certain new and useful Improvements in Radiotelegraphy, of which the following is a specification.

The invention relates to a transmission system of radio telegraphy, and particularly continuous-oscillation radio telegraphy, involving variations in antenna inductance. One widely used form of signaling with continuous oscillations consists in varying the antenna inductance, either by short-circuiting a portion of the antenna loading coil or by short-circuiting a compensation helix arranged in the antenna circuit. This variation in inductance produces a variation in wave length and to produce a given percentage change in wave length, the antenna inductance must be changed a certain amount. The antenna current through the inductance changed sets up a certain voltage, which, multiplied by the antenna current, gives the kilo-volt-amperes to be handled by the key or relay or other signaling instrument. On account of practical considerations, the kilo-volt-amperes which can be handled by one pair of contacts is limited and hence it has been necessary to employ a plurality of contacts.

An object of the present invention is to provide a system whereby the kilo-volt-amperes which can be successfully handled by one pair of contacts is greatly increased and consequently the number of contacts reduced to a minimum.

A further object of the invention is to provide a system which makes the load on the key such that it can be successfully handled with air as the contact dielectric instead of making the contact dielectric suit the load, for example, by immersion in oil to reduce sparking.

The invention possesses other advantageous features, some of which, with the foregoing, will be set forth at length in the following description where I shall outline in full, that form of the invention which I have selected for illustration in the drawings accompanying and forming part of the present specification. In said drawings I have shown one specific form of the apparatus of my invention, but it is to be under-

stood that I do not limit myself to such form, since the invention as expressed in the claims may be embodied in a plurality of forms.

Referring to said drawings:

Figure 1 is a diagrammatic representation of a radio telegraphy transmission system illustrating my invention.

Fig. 2 is a diagrammatic representation of the system of my invention when employed in very high powered stations.

Fig. 3 is a cross section of the lower turn of the inductance and the loop.

I have found that the load which can be handled with one pair of contacts is limited mainly by the voltage and not by the current and by making the amperes high and the voltage low, a much greater load can be successfully handled by one pair of contacts. Heretofore, it has been the practice to employ a relay for opening and closing the short-circuit around the helix in the antenna circuit, and the relay was operated by a key in the local circuit. This necessitated insulating the local circuit from the high potential oscillating circuit, and also permitted the contacts to operate only with the antenna current instead of with a higher current value. Therefore, less kilo-volt-amperes could be handled by one pair of contacts, because the voltage was high, and the voltage across the contacts limits the kilo-volt-ampere they can handle to a very great extent. My invention overcomes these difficulties, permitting only a low potential in the signaling circuit.

The ordinary continuous oscillation transmission system may be represented by an arc 2 supplied with current from the generator 3. One side of the arc is grounded and the other side is connected to the antenna 4, through the variable inductance or loading coil 5. This is the usual form of arc radio transmission systems, so that it is unnecessary to enter it to the details thereof. Instead of signaling by short-circuiting a portion of the inductance 5, I place a circuit which may consist of one loop 6, in inductive relation with the inductance, and preferably the lower turn thereof. The loop 6 acts as the secondary of a step-down transformer, of which the coil 5 is the primary, and the voltage in the loop is much lower than in the coil. A relay or key, preferably a relay 7, is arranged in the loop cir-

cuit and signaling is accomplished by opening and closing the relay.

In very high powered stations, where the antenna current may be, for instance, 300 amperes and the loop current 600 amperes, it is impractical to endeavor to control the loop current with one pair of contacts, because the loop-reactive voltage becomes too high, and under such and similar conditions 5 I provide means for employing a plurality of pairs of contacts, so arranged that each pair handles a given load, regardless of whether the contacts are closed simultaneously or in 10 succession. To produce this result, I divide 15 the loop into a plurality of segments 8, preferably of equal length, by conductors 9 connected at one end to the loop at equally spaced points and connected together at the other ends. In each segment I insert a relay 7, the solenoids 12 of the relays being 20 connected in series in the local circuit, with the key 13. This arrangement equalizes the 25 loads on the pairs of contacts, so that extremely large loads may be handled.

25 The loop 6 is preferably of the same diameter as the inductance coil 5 and is axially aligned therewith and spaced apart from the lower turn of the coil a sufficient distance to provide for ample insulation of the 30 loop from the coil.

I claim:

1. A radio telegraphy transmission system including an antenna circuit, an inductance coil in said circuit, a plurality of sector circuits inductively connected to said inductance coil, and means for opening and closing the sector circuits.

2. A radio telegraphy transmission system including an antenna circuit, an inductance coil in said circuit, a plurality of circuits permanently equally inductively connected to said coil and means for opening and closing said plurality of circuits.

3. A radio telegraphy transmission system including an antenna circuit, a step-down transformer having its primary in 45 the antenna circuit, a plurality of conductors short-circuiting different sections of the transformer secondary, and means in the short-circuited sections for opening and closing the circuit through the said sections.

4. A radio telegraphy transmission system including an antenna circuit, a step-down transformer having its primary in the antenna circuit, interconnected conductors 55 connected to spaced points on the transformer secondary, and means in the secondary between the points of connection of the interconnected conductors for opening and closing the secondary.

5. A radio telegraphy transmission system including an antenna circuit, an inductance coil in said circuit, a loop inductively associated with said coil, a plurality of interconnected conductors connected to the 65 loop at spaced points and dividing the loop into a plurality of segments, and means in each segment for opening and closing the circuit in each segment.

6. A radio telegraphy transmission system including an antenna circuit, an inductance coil in said circuit, a loop inductively associated with said coil, a plurality of interconnected conductors connected to the 70 loop at spaced points and dividing the loop into a plurality of segments, a switch in each segment and means for operating said switches.

7. A radio telegraphy transmission system including an antenna circuit, an inductance coil in said circuit, a loop inductively associated with said coil, a plurality of interconnected conductors connected to the 75 loop at spaced points and dividing the loop into a plurality of equal segments, a switch in each segment and means for operating said switches.

In testimony whereof, I have hereunto set my hand at San Francisco, California, this 11th day of September, 1917.

LEONARD F. FULLER.
